CLAIM

The ornamental design for a musical instrument bag, as shown and described.

DESCRIPTION

1. Musical instrument bag

1.1) Perspective

1.2) Top

1.3) Bottom

1.4) Perspective

1.5) Perspective in a second position of use

The present design is a musical instrument bag for operation and transportation of a percussion instrument keyboard. The musical instrument bag is shown with a symbolic break in its length; the appearance of any portion of the article between the break lines forms no part of the claimed design.
